UNITED STATES PATENT OFFICE.

JOHN S. THURMAN, OF ST. LOUIS, MISSOURI.

PNEUMATIC RENOVATOR.

No. 797,241.

Specification of Letters Patent.

Patented Aug. 15, 1905.

Application filed March 24, 1904. Serial No. 199,760.

To all whom it may concern:

Be it known that I, JOHN S. THURMAN, a citizen of the United States, residing at the city of St. Louis, in the State of Missouri, have invented a certain new and useful Pneumatic Renovator, of which the following is such a full, clear, and exact description as will enable any one skilled in the art to which it appertains to make and use the same, reference being had to the accompanying drawings, forming part of this specification.

My invention relates to pneumatic renovators, and more particularly to that class of renovators consisting of a casing provided with an inlet in the bottom in combination with a blast-nozzle adapted to discharge a jet of air into or through the article to be cleaned and thence into said opening.

My invention consists in various novel features and details of construction, all of which are described in the following specification and pointed out in the claims affixed hereto.

In the accompanying drawings, which illustrate two forms of renovator made in accordance with my invention, Figure 1 is a vertical central section. Fig. 2 is a section on the line 2 2 of Fig. 1. Fig. 3 is an enlarged section of the hand-grip. Fig. 4 is a sectional view showing the manner of forming one of the blast-nozzles. Fig. 5 is a side elevation, on a reduced scale, showing the complete renovator with the bag attached. Fig. 6 is a top plan view of the parts shown in Fig. 5, the dust-chamber and bag being removed. Fig. 7 is a section on the line 7 7 of Fig. 3. Fig. 8 is a section on the line 8 8 of Fig. 9. Fig. 9 is partly a section and partly a side elevation of a modified form of renovator, and Fig. 10 is a section on the line 10 10 of Fig. 9.

Like marks of reference refer to similar parts in the several views of the drawings.

Referring first to Figs. 1 to 7, inclusive, which illustrate a form of renovator more particularly adapted for renovating carpets, 15 is the casing or body of the renovator. The bottom of the casing 15 is adapted to rest upon the carpet or other article to be cleaned, and said bottom is provided with a pair of inlet-openings 16. Adjacent to the inlet-openings 16 are the blast-nozzles 17. These nozzles are adapted to discharge compressed air at an angle to the lower face of the renovator and into and through the carpet or other article to be renovated and thence up through the inlet 16 to the interior of the casing 15. The blast-nozzles 17 are partly formed by a wall or partition 18, extending across the casing 15, and partly by a removable block or casting 19, which is secured to this wall or partition 18, as shown in Figs. 1 and 2. In each of the blast-nozzles 17, adjacent to the outlet thereof and in the air-passage, are a number of spreading-posts 20. (Best shown in Fig. 4.) These spreading-posts 20 are cuneate in form and have their apices alternately disposed toward the inlet and the outlet of the nozzle, as shown in this figure, so as to thoroughly distribute the air along the nozzle 17, and thus secure uniform pressure throughout the length of the nozzle. The block or casting 19 is secured to the casing 15 by means of bolts or screws 70. In order to separate the block slightly from the partition 18, against which it rests, I interpose between the said parts a thin strip 71 of paper or other similar material, and thus regulate the size of the mouths 17 of the blast-nozzle. The admission of air to one or the other of the nozzles 17 is controlled by means of a cylindrical valve 21. This valve is preferably surrounded by a bushing 22, in which the said valve works. The bushing 22 is provided with passages 23, communicating with the nozzles 17, and also with passages 24, communicating with a cross-passage 25. The ends of this passage 25 extend along the ends of the renovator and connect with a common inlet 26, to which is secured one end of a short flexible tube 27. Adjacent to the flexible tube 27 is a second flexible tube 28, which leads to an internal blast nozzle or jet 29, Fig. 1, which is centrally located in a short discharge-pipe 30, threaded in and extending upwardly a short distance from the outlet of the casing 15. The ends of the valve 21 are provided with arms 32, to which are pivoted the bifurcated ends 33 of the handle. The movement of the arms 32 is limited by lugs 34, arranged at one or both ends of the casing 15. Extending from the bifurcated ends 33 of the handle are a pair of pipes 35 and 36, respectively, which form the shaft of the handle. The pipe 35 is connected to the flexible tube 27, hereinbefore described, and the pipe 36 is connected to the flexible tube 28. Secured to the ends of the pipes 35 and 36 is the grip 37, forming the upper end of the handle. Secured to the lower end of the grip 37 is a flexible pipe 38, which supplies the compressed air to the renovator. This pipe 38 opens into a chamber 39, provided with two outlets:

These outlets are normally closed by means of valves 40 and 41, respectively, Fig. 7. Leading from the valve 40 to the end of the pipe 35 is a passage 42, and leading from the valve 41 to the end of the pipe 36 is a passage 43. The valve 40 is controlled by a finger-piece 44, arranged at the back of the grip 37. The finger-piece 44 is pivoted to the grip at 47 and bears upon the end of the stem of the valve 40, so as to operate the said valve against the pressure of the spring 46. The valve 41 is controlled by a similar finger-piece 45 in the loop of the grip 37. The finger-piece 45 is pivoted at 48 and bears against the end of the stem of the valve 41, so as to operate said valve against the spring 46. 50 is the dust-collecting chamber, which is preferably cylindrical in form and preferably made of sheet metal. The chamber 50 has an opening in its bottom of substantially the same diameter as the short pipe 30, extending upwardly from the casing 15, and secured to the upper face of the bottom is a short tube 51, adapted to fit the said pipe 30. The pipe or tube 51 is also provided with an extension 52, threaded into its upper end. The extension 52 is closed at its upper end by means of a globular valve 53. This valve is prevented from displacement by means of a wire cage 54, which is preferably made separable from the tube or pipe 52. The tube or pipe 52 fits against the end of the discharge-pipe 30, as clearly shown in Fig. 1, so as to make a flush joint with it, and thus allow no place for the escape or lodgment of dust. The upper edge of the dust-chamber 50 is provided with a turned-over edge or roll 55, by means of which the bag 56, of cloth or other foraminous material, is secured in place. In order to hold the bag distended, the chamber 50 is provided with a clamping device 57, in which is secured a rod 58, corresponding to the contour of the bag and to which the bag is secured at several points, as shown in Fig. 5. Owing to the construction above described, the dust-chamber 50, together with the bag 56, can be lifted off of the renovator when they become dirty and replaced by a clean dust-chamber and bag, as the parts simply slip over the short discharge pipe or tube 30.

In Figs. 8 and 9 I have shown a modified form of my apparatus which is especially adapted for cleaning furniture. In this device in place of the casing 15 I use a casing 60, having but a single inlet-opening in its bottom. 61 is the blast-nozzle, which discharges the air into and through the material to be cleaned and thence into the opening 62 in the bottom of the casing 60. In this form of apparatus the casing is not provided with a dust-chamber or dust-collecting bag, but the air passes out through a pipe 64, which in turn communicates with a flexible pipe 65, leading either to a stationary dust-collector (not shown) or to any suitable

place where the dust is to be discharged. The grip 37 is the same as that previously described in connection with the form of renovator shown in Figs. 1 and 6 and need not be again particularly described. The pipe 35 of the handle leads to the blast-nozzle 61 through a passage 72, formed in the casing 60. The pipe 36 leads to the internal nozzle or jet 63 through a passage 73, formed in the casing 60. The nozzle 61 is formed partly by the rear wall of the casing 60 and partly by a removable portion 74, secured against the said rear wall by means of screws or bolts 75. These screws or bolts 75 pass through spreading-posts 76, formed in the passage of the nozzle 61. The spreading-posts 76 are similar to the spreading-posts 20, hereinbefore described.

In the operation of my renovator the casing 15 is moved over the carpet or other article to be cleaned in either direction by means of the grip 37. When the renovator is moved forward, the action of the bifurcated ends 33 on the arms 32 moves the valve 21 in position to discharge through the forward blast-nozzle 17, the movement of the arms being limited by the stops 34. When the casing is moved backward, the arms are thrust against the opposite stops 34, so as to throw the valve in position to discharge through one or the other nozzle, so that it always issues in the direction in which the renovator is traveling. By means of the finger-pieces 44 and 45 a perfect control is had over the admission of air to both the blast-nozzle and the internal nozzle or jet 29. The action of the compressed air rebounding from the surface to be cleaned forces the air up through the outlet-pipes 30 and 52 to the dust-collecting chamber 50. This action can also be increased by admitting air through the internal nozzle or jet 29 by means of the finger-piece 45. Once the chamber 50 becomes filled with dust or the foraminous bag becomes clogged the chamber and bag can be together removed from the renovator, as hereinbefore described, and a new chamber and bag substituted.

The operation of the renovator shown in Figs. 8 and 9 is similar to that above described except that the renovator is intended to always be moved in a forward direction. The valves in the grip 37 give perfect control over the admission of air both to the blast-nozzle and to the internal jet.

Having fully described my invention, what I claim as new, and desire to secure by Letters Patent of the United States, is—

1. In a pneumatic renovator, the combination with a casing, of a blast-nozzle, a removable dust-chamber carried by said casing and provided with an opening in its bottom for the dust-laden air from said casing, and means for preventing the return of the dust-laden air from said dust-chamber to said casing.

2. In a pneumatic renovator, the combination with a casing, of a blast-nozzle, a removable dust-chamber carried by said casing and provided with an opening in its bottom for the dust-laden air from said casing, a conduit carried by said dust-chamber and extending upwardly from said opening, and a valve for closing said conduit.

3. In a pneumatic renovator, the combination with a casing provided with a blast-nozzle, of a tube carried by said casing, a dust-chamber slidably mounted on said tube, and a valve for controlling the communication between said tube and dust-chamber.

4. In a pneumatic renovator, the combination with a casing provided with a blast-nozzle, of a tube carried by said casing, a dust-chamber slidably mounted on said tube,

and a valve for controlling the communication between said tube and dust-chamber, said valve being carried by and removable with said dust-chamber.

5. In a pneumatic renovator, the combination with a casing provided with a blast-nozzle, of a tube carried by said casing, a dust-chamber having an inwardly-projecting tube adapted to slide over said first-named tube and project above it, and a valve carried by said second-named tube.

In testimony whereof I have hereunto set my hand and affixed my seal in the presence of the two subscribing witnesses.

JOHN S. THURMAN. [L. S.]
